UNITED STATES PATENT OFFICE.

ALEXANDER H. WAGNER, OF PIMLICO, ENGLAND.

IMPROVEMENT IN SAFETY-DOORS FOR CHURCHES.

Specification forming part of Letters Patent No. 42,719, dated May 10, 1864.

To all whom it may concern:

Be it known that I, ALEX. H. WAGNER, of Pimlico, in the county of Middlesex, England, temporarily residing at Windsor, Canada West, have invented a new and Improved Safety-Door for Churches, &c.; and I do hereby declare that the following is a full, clear, and exact description of the same, reference being had to the accompanying drawings, making a part of this specification, in which—

Figure 1 represents an outside view of my invention. Fig. 2 is an inside view of the same. Fig. 3 is a horizontal section of the same.

Similar letters of reference in the three views indicate corresponding parts.

The object of this invention is to construct the doors of a church or other public building so that the same in ordinary cases open inwardly, the same as doors of the usual construction, but in case of fire or other accident, whereby the assemblage in the building is compelled to break up in great haste, by a slight touch of a lever or other suitable contrivance the door is made to swing outward with an increased area, and the obstruction offered by said door to the egress of the people from the building is considerably decreased.

The nature of my invention and its peculiar advantages will be readily understood from the following description.

A represents the door of a church or other public building in which large assemblages of people congregate, either for worship or for other purposes. This door is hung on hinges *a*, which are secured to the frame *B* in the usual manner, and it opens inwardly, the same as the doors in most such buildings.

If a large assemblage has congregated in the building, and a fire or other accident occurs which renders it desirable for everybody to leave said building as quick as possible, a door of the ordinary construction, and particularly when the same opens inwardly, is inadequate for the occasion. It is liable to become clogged up or closed by the people in their great eagerness to rush out and the haste with which in

such cases each person is trying to save his or her own life, and the inadequate means of egress in public buildings of the ordinary construction has been the cause of great loss of life.

In order to facilitate the egress through the door and to prevent its being clogged up or closed, I have hung the frame *B* of my door on hinges *b*, so that the same swings outwardly, and I fasten it by means of eyebolts *c* and loops *d*. The eyebolts are firmly inserted in the inner surface of the frame, and when the same is closed they pass through mortises in a strip, *C*, of wood or metal, which is secured to the inside edge of the opening in which the frame is made to swing. The loops *d* are firmly attached to the inner side of the strip *C* in such a position that when the frame is closed a rod, *f*, can be freely passed through the eyes of the bolts *c* and the loops *d*.

In practice the frame will be secured by means of two eyebolts and two loops—one above and the other below—and the bolts or rods which fasten the same are connected to a lever, *D*, on opposite sides from its fulcrum, as clearly shown in Fig. 2, so that by depressing the end of said lever both rods are withdrawn simultaneously, and the frame, together with the door, is allowed to swing out, as shown in Fig. 3. I do not wish to confine myself, however, to any peculiar way of securing the frame by means of the lever *D* and eyebolts and loops *c d*, as this object can be effected in various ways.

What I claim as new, and desire to secure by Letters Patent, is—

1. The combination of a door, *A*, opening inward, with a frame, *B*, hung on hinges and opening outward, substantially in the manner shown and described.

2. The application to the frame *B* and door *A*, constructed as described, of a lever, *D*, or its equivalent, so that by a slight touch of said lever the frame is liberated and allowed to swing open.

ALEXANDER H. WAGNER.
